UNITED STATES PATENT OFFICE

MAX S. GOLDSMITH AND BENJAMIN HARIG, OF CINCINNATI, OHIO, ASSIGNORS TO THE GOLDSMITH METAL LATH COMPANY, OF CINCINNATI, OHIO, A CORPORATION OF OHIO

MOUNTING FOR REMOVABLE TILE

Application filed October 12, 1927, Serial No. 225,666. Renewed November 3, 1928.

This invention relates to metal tiles and means for supporting same upon soffits, as used in plastic or concrete construction.

An object of the invention is to provide a simple means for mounting tiles upon soffits and the like and wherein the mounting means co-operates with the tiles for effecting substantial connection between the tiles and such mounting means.

Another object of the invention is to provide means for the purpose indicated that are simple in construction and application and that may be fabricated in such manner and from such materials as to render inconsequential the cost incident to production thereof.

These and other objects are attained by the means described herein and disclosed in the accompanying drawings, in which:

Fig. 1 is a cross sectional view showing a structure embodying the invention and for co-operative relationship with a temporary supporting structure.

Fig. 2 is a sectional view on line 2—2 of Fig. 1.

Fig. 3 is a sectional view on line 3—3 of Fig. 2.

Fig. 4 is a detailed perspective view of a supporting lug or plate forming a detail of the invention.

Fig. 5 is a sectional view on line 5—5 of Fig. 2.

The soffits 10 are supported by suitable shoring 11. The soffits support tiles 12, generally of sheet metal. Between adjacent tiles 12 a concrete beam 13 is customarily provided and over the tiles a concrete slab 14 is provided. This invention relates to the means employed for mounting and securing the tiles 12 upon soffits 10.

The side walls or legs 15 of the tiles are provided with suitable apertures 16. It is to be understood that the apertures may be provided at various elevations from the lower edges of the arms 15 whereby to adjust-

ably position the tiles upon the soffits for providing beams 13 of various heights. It is also to be understood that apertures such as 16 are provided in sets of two or more, each aperture of each of such sets being spaced substantially equidistant from the lower edges of the sides or legs of the tile. Support plates 17 are provided for mounting upon the tiles by having a projection 18 formed on such plates extending through the apertures 16 in the tiles. Each of the lugs 18 is provided with an aperture 19 through which an ordinary nail 20 may be inserted. It is to be noted that the plates 17 are provided with upstanding flanges 21, one each of which flanges, is disposed on opposite sides of the lug 18, and that the distance between the flanges 21 and the apertures 19 for receiving the nail 20, is such that upon driving a nail through the aperture 19, the nail shank 22 and head 23 thereof frictionally engage the tile and retain same in substantially rigid contact upon the flanges 21. Separation of the nail, plate 17, and tile, may be readily effected by driving the nail from the aperture 19 and by subsequently flexing the arm 15 of the tile to such extent as to clear the lug 18.

Each of the plates 17 comprises a flat base member 25 longitudinally of which is provided a rib or corrugation 26 that is projected beyond the base and such projected portion of the rib constitutes the indicated lug 18. The base portion disposed on opposite sides of the rib 26, is developed into the upstanding flanges 21 aforesaid, by severing the said flange members from the rib member 26 and by turning said flange members at substantially right angles to the base 25 adjacent the lug 18. The rib 26 is provided with a nail hole 27, substantially identical with the nail hole 19 and through the hole 27 there may be driven a suitable fastening means such as nail 28 for securing

the base plate and tile associated therewith upon the soffit 10.

In the practical application of the invention the plates 17 are mounted upon the tiles 5 before the tiles are assembled upon or over the soffits. After the concrete beams and slabs 13 and 14, have been formed and set, the nails 20 are removed and the tiles may be withdrawn without disturbing the plates 10, 17, soffits 10 and shoring 11. The tiles may therefore be used repeatedly in the same structure undergoing erection. After the concrete beams and slabs have hardened to a sufficient degree to permit removal of the 15 soffits and shoring, the plates 17 may be detached from the concrete beams and may be re-used.

It is preferable that the rib 26 of the plates be made substantially the same width 20 as the diameters of the apertures provided in the tiles, whereby to effect a fairly snug connection between the plates and the tiles. The rib also serves to re-inforce and strengthen the plate structure.

25 What is claimed is:

1. The combination with a perforated tile and a support of a plate comprising a perforated rib and a flange disposed adjacent said rib, the perforated rib adapted for insertion 30 through a perforation in the tile and means insertable in the perforation in the rib for securing the plate to the tile and for holding the tile in frictional contact upon and between the flange and the fastening means, 35 the plate adapted for mounting upon the support.

2. As a new article of manufacture a sheet metal plate comprising a flat body flanged at its one end, and a perforated rib extending 40 in substantial parallelism with the body portion and projecting beyond the flanged portion of the body.

3. As a new article of manufacture a plate comprising a flat body having a central 45 perforated rib and flanges extending from the body and disposed on opposite sides of the rib, the rib extending in substantial parallelism with the body and having a perforation therein disposed beyond the 50 flanges carried by the body.

4. The combination with a pair of suitably supported spaced soffits, of a tile comprising depending side walls for insertion between said soffits, independent brackets 55 on the soffits having extensions for projecting through selected portions of the side walls for supporting the tiles in predetermined relation to the soffits and means extending transversely through the brackets 60 on opposite sides of said side walls to retain the brackets, tile and soffits against relative movement.

5. The combination with a pair of suitably-supported spaced soffits, of a tile having 65 perforated walls, tile supports each com-

prising a body portion adapted to be secured upon the upper face of the soffit and an extended rib portion adapted to project through one of the perforations in the tile, and means abutting opposite sides of the tile 70 wall adjacent the inserted rib portion for securing together the tile and tile support and precluding relative movement thereof.

In testimony whereof, we have hereunto subscribed our names this 4th day of 75 October, 1927.

MAX S. GOLDSMITH.
BENJAMIN HARIG.
